DESIGN FOR A FILLING HORN

Raymond W. Smith, Chicago, Ill.

Application May 7, 1942, Serial No. 106,817

Term of patent 3½ years

To all whom it may concern:

Be it known that I, Raymond W. Smith, a citizen of the United States, residing at Chicago, in the county of Cook and State of Illinois, have invented a new, original, and ornamental Design for a Filling Horn, of which the following is a specification, reference being had to the accompanying drawing forming a part thereof.

In the drawing:

Fig. 1 is a perspective view of a filling horn showing my new design;

Fig. 2 is a front elevational view thereof; and
Fig. 3 is a side view thereof.

I claim:

The ornamental design for a filling horn, as shown.

RAYMOND W. SMITH.
